APPARATUS FOR FEEDING AGGREGATE

Stewart L. McCurdy, Pittsburgh, Pa.

Application December 8, 1937, Serial No. 178,679
Renewed August 23, 1939

8 Claims. (Cl. 302—53)

The invention relates to pneumatic apparatus for feeding aggregate, such as concrete, but is applicable for feeding any finely divided material. The invention has for its principal objects, 5 the provision of an improved apparatus in which the feed control is automatic and which does not depend for its efficiency upon the skill of the operator; the provision of an apparatus in which any tendency to stall in starting is obviated; and 10 the provision of an apparatus which will feed uniformly without clogging or attention on the part of the operator and with a high degree of efficiency as to volume delivered and compressed air requirements.

15 One of the important features of construction contributing to the above results, is the provision of a false bottom wall or diaphragm above the delivery outlet mounted for free oscillatory or vibratory movement, with a separate air supply 20 theretherebeneath, so that in the operation of the apparatus, and due to varying conditions of air pressure on the two sides of the bottom wall, such wall will vibrate up and down producing an agitation of the material as it enters the outlet 25 and providing for an automatic variation of air supply along the bottom wall of the outlet. This 30 vibrating action keeps the aggregate loose and in movement at the critical point of the apparatus, in which stoppage is most liable to occur. The material is thus fed in a series of slugs which merge into a uniform flow by the time the material merges from the outlet conduit.

A second important feature contributing to the efficiency of the apparatus in starting, is the arrangement of the air supply, so that on opening 35 the single control valve, the air is supplied to different parts of the apparatus in a sequence which will prevent stalling, the arrangement being such that the compressed air is first supplied to the outlet conduit, then above the material in the 40 hopper and below the false bottom or diaphragm. This simplifies the duties of the operator and insures the proper application of air in starting after each charging of the hopper. Certain 45 embodiments of the invention are illustrated in the accompanying drawings, wherein:

Figure 1 is a vertical section through the apparatus. Fig. 2 is an end elevation partially in section. Fig. 3 is a section on the line III—III of Fig. 1. And Figs. 4 and 5 are partial vertical sections showing modifications.

Referring to the drawings, 6 is a container of hopper form having a sliding gate 7 past which the aggregate is supplied from time to time by 55 means not shown and constituting no part of the

present invention, the gate being operated by means of an air cylinder 8 whose piston rod 9 is connected to a bracket 10 at the rear end of the gate. The neck 11 of the container is flanged as indicated in Fig. 2 with the edges of the gate 5 in opposition thereto. The side and rear edges of the gate have welded thereto the angles 12, 12 (Fig. 2) and 13 (Fig. 1) whose horizontal flanges lie beneath and oppose the flanges on the neck, a gasket being interposed between such flanges, so 10 as to make the gate air tight when air pressure is supplied to the upper end of the container forcing the gate upward. At its front end the gate is made tight by coming against the gasket. Supporting guides for the horizontal flanges 12, 12 15 are provided in the form of angle members 15, 15 (Fig. 2) mounted on the screw supports 16, 16.

In order to keep the flange surfaces of the gate 20 clean, a perforated pipe 17 is located in the angle 13, as indicated in Fig. 1, and has one end connected to the flexible air supply hose 18. This connection also serves to apply the air pressure required in the container above the aggregate. The air thus supplied flows along the flange surfaces and blows out the dust and dirt, the flow 25 into the container occurring between the neck flanges and the bottom surface of the gate at its edges when the gate is forced upward by the air pressure, so that it no longer contacts with the neck flanges. The cleaning effect of the air is 30 assisted at suitable intervals by admitting some water into the pipe 18. This is accomplished through the connection 19 (Fig. 1) provided with a valve 20. Air is supplied to the flexible hose 18 35 from the connection 21 leading to the T 22 (Fig. 2) to which air is supplied as later described.

The container, or hopper, is provided at its lower end with a rectangular outlet 23 located, as indicated in Fig. 1, discharging to the conduit fitting 24 which becomes circular in cross section 40 at its outer end where it is attached to the conduit pipe 25 leading to the point of delivery of the apparatus. Air under pressure is supplied to the fitting 24 from the main supply pipe 26 (Fig. 2) via the pipe connections 27, 28, 29 and 30, the 45 latter of which takes into the fitting.

The container 6 is provided with a false bottom plate or diaphragm 31 hinged at its upper end on the transverse rod 32 whose ends are suitably secured to the side walls of the container. A baffle 50 33 welded to the walls of the container closes the space between the upper edge of the plate 31 and the walls of the container thereabove, so that the aggregate in the container is directed downwardly and to the right over the plate 31 to the outlet 55

23. A space 34 is thus provided below the plate 31, and this space is supplied with air under pressure from the pipe 35, such pipe being connected to the pipe 28 via the connections 36, 37 and 38 (Figs. 2 and 3). The plate 31 fits at its side edges into the container, so that it is free to vibrate or oscillate freely and has its lower end normally spaced away from the bottom wall of the container a slight distance as indicated in Fig. 1, stop members 39 at the side edges of the plate serving to prevent complete closure at this point. An outlet slot is thus provided leading from the space 34 to the conduit 24 along the bottom wall thereof, of which space is automatically increased a varying amount under operating conditions since the plate is free to oscillate or vibrate.

The flow of air from the supply pipe 26 to all three connections 18, 30, and 35, is controlled by a single valve 37a located in the pipe 27, such valve being moved to open and closed positions by the handle 37b. When the valve is moved to open position, air is thus supplied by the hose 18 to the casing above the aggregate, to the space 34 below the false bottom plate 31 by the pipe 35, and to the conduit 24 by the pipe 30. The air supplied through the pipes 30 and 35 is essential in order to give an uninterrupted feed of material through the conduit. The air pressure above the aggregate presses it downward to the outlet 23, but would pack at this point and in the conduit, unless loosened and urged along by the air supplied to the conduit and below the lower edge of the plate 31. An aggregate fed under air pressure has a tendency to move in an uneven manner, so that the air pressure in the apparatus rises and falls due to the release of pressure as the mass starts to move and to the building up of pressure when the mass stops momentarily. These conditions cause the plate 31 to vibrate 40 up and down throughout the operation and loosen the material at the outlet 23 which is the point at which the material is apt to become stalled. Further, when a stoppage occurs at 23, the pressure in the space 34 builds up moving 45 the plate upward and permitting more air to discharge below the mass in the outlet, thus automatically giving the necessary force to free the mass by carrying away the bottom layer. The operation thus requires no special skill or 50 attention on the part of the operator.

The air supply arrangement also insures a feed of the aggregate when the apparatus is first started. At such time, the pressure of the material at the outlet 23 is a maximum tending to prevent the starting of a feed through the conduit. The air connections, as shown, give an application of air through the connection 30 to the conduit before pressure has a chance to build up above the aggregate, due to the relatively shorter, larger connection to the conduit, as compared with those leading to the upper end of the container. With this arrangement, a proper starting is secured by manipulating only the single valve 37a, which may be opened full and left in such position through substantially the entire feeding cycle. The space 34 is provided with a clean-out opening normally closed by the cover plate 40.

Fig. 4 illustrates a modification in which the 70 false bottom or diaphragm comprises a plate 41 which is not pivoted like the plate 31 of the Fig. 1 construction, but which can vibrate or oscillate due to the flexibility of the metal. The plate is secured at its upper edge to the wall of the container preferably by welding to the mem-

bers 42 and 43 which are in turn welded to the wall of the container, the side edges of the plate being free, but closely adjacent the side walls of the container, as in the Fig. 1 construction, so that practically all of the air supplied to the 5 space 34 discharges through the slot 44 at the lower end of the plate.

Fig. 5 illustrates a modification in which the container 6a is longer and of less height than the containers of Figs. 1 and 4, this type of container being of advantage where the head room is limited. In order to provide for the more ready emptying of a container of this type, the swinging plate 45 is provided in order to give a feed of aggregate from the area 46 of the container. 10 This plate is secured at one edge to a transverse shaft 47 mounted for rotation in bearings in the side walls of the container and provided at one end, exterior of the casing, with a crank arm 48. 15 This crank arm is swung from the hydraulic cylinder 49 provided with a plunger whose piston rod 50 is connected to the crank as shown. As the container empties, the plate 45 is swung upward toward the dotted line position A to cause the aggregate in the area 46 to feed to the right 20 onto the plate 51, which is hinged to the shaft 47 and free to vibrate or oscillate in the same manner as the plate 31 of the Fig. 1 construction. Air under pressure is supplied to the apparatus as in the Fig. 1 construction, the air supplied to the space 52 beneath the plates 45 and 51 from the pipe 52a assisting in moving the plate 45, as the container is emptied.

While the air supply arrangement, as illustrated and described, is the preferred one, this detail of construction is subject to some modification without impairing the operation materially. Three air supply connections are shown in all forms of the apparatus, but the device can be operated to feed more slowly and with some- 40 what less efficiency, when the connection leading to the space above the false bottom plate is dispensed with. Under these conditions, the weight of the material causes it to feed downward to the outlet 23 by gravity, and a sufficient air pressure accumulates above the mass of material, due to the filtration upward therethrough of a part of the air supplied through the air supply pipe leading to the space beneath the false bottom plate and through the pipe 30. 50

What I claim is:

1. In combination in a pneumatic conveyor, a casing having an inlet for material at its top and an outlet at its lower side; a conduit leading laterally from said outlet, a gate for said inlet, 55 an inclined plate constituting a false bottom for the container with its lower edge terminating adjacent the end of the conduit and spaced above the bottom of the container, said plate being mounted so that said edge is free to oscillate up and down, and means for supplying air under pressure into the container above the inclined plate and into the space below such plate.

2. In combination in a pneumatic conveyor, a casing having an inlet for material at its top 65 and an outlet at its lower side, a conduit leading laterally from said outlet, a gate for said inlet, an inclined plate constituting a false bottom for the container with its lower edge terminating adjacent the end of the conduit and spaced above 70 the bottom of the container, said plate being mounted so that said edge is free to oscillate up and down, and three connections for supplying air under pressure for promoting a feed of material from the container, one of which leads into 75

the upper portion of the container, another of which leads into the space below the inclined plate, and the third of which leads into the conduit adjacent said outlet.

5. 3. In combination in a pneumatic conveyor, a casing having an inlet for material at its top and an outlet at its lower side, a conduit leading laterally from said outlet, a gate for said inlet, an inclined plate constituting a false bottom for the container with its lower edge terminating adjacent the end of the conduit and spaced above the bottom of the container, said plate being hinged at its upper edge so that the lower edge is free to vibrate up and down and means for supplying air into the container above the inclined plate and into the space below such plate.

4. In combination in a pneumatic conveyor, a casing having an inlet for material at its top and an outlet at its lower side, a conduit leading laterally from said outlet, a gate for said inlet, an inclined plate constituting a false bottom for the container with its lower edge terminating adjacent the end of the conduit and spaced above the bottom of the container, said plate being flexibly mounted at its upper edge so that the lower edge, in opposition to the end of the conduit, is free to vibrate vertically, and means for supplying air into the container above the inclined plate and into the space below such plate.

5. 5. In combination in a pneumatic conveyor, a casing having an inlet for material at its top and an outlet at its lower side, a conduit leading laterally from said outlet, a gate for said inlet, an inclined plate constituting a false bottom for the container with its lower edge terminating adjacent the end of the conduit and spaced above the bottom of the container, said plate being mounted for free oscillatory movement about its upper edge, an air pressure supply pipe, a control valve therefor and three connections on the outlet side of the valve leading (1) to the upper portion of the container (2) to the conduit adjacent its inlet and (3) to the space beneath said plate, the connection to the conduit being the shortest of the three, so that the first application of air is to the conduit.

6. In combination in a pneumatic conveyor, a casing having an inlet for material at its top and

an outlet at its lower side, a conduit leading laterally from said outlet, a gate for said inlet, slidably mounted on guideways, an inclined plate constituting a false bottom for the container and with its lower edge terminating adjacent the end of the conduit and spaced above the bottom of the container, said plate being mounted for swinging movement about its upper edge, a connection for supplying air along said guideways to the upper end of the container to clean such guideways and apply downward pressure to the material in the container, means for supplying water to said connection to promote the cleaning action of the air, and a second connection for supplying air under pressure to the space beneath said plate. 5 10 15

7. In combination in a pneumatic conveyor, a casing having an inlet for material at its top and an outlet at its lower side, a conduit leading laterally from said outlet, a gate for said inlet, an inclined plate constituting a partial false bottom for the container with its lower edge terminating adjacent the end of the conduit and spaced above the bottom of the container, said plate being mounted so that it is free to oscillate up and down, a second plate also constituting a 20 25 partial false bottom pivoted at the upper edge of the first plate and oppositely inclined when the container is filled with material, power means for swinging the second plate upward about its pivoted edge as the container empties, and means for supplying air into the container above the inclined plates and into the space below such plates. 30

8. In combination in a pneumatic conveyor, a casing having an inlet for material at its top 35 and an outlet at its lower side, a conduit leading laterally from said outlet, a gate for said inlet, an inclined plate constituting a false bottom for the container with its lower edge terminating adjacent the end of the conduit and spaced above 40 the bottom of the container, said plate being mounted for free vibratory movement up and down about its edge which is remote from the conduit, and means for supplying air under pressure into the container below said plate and to 45 said conduit adjacent its inlet.

STEWART L. McCURDY.
